US0D1044105S

(12) United States Design Patent (10) Patent No.: US D1,044,105 S
(45) Date of Patent:  Sep. 24, 2024

(54) LAMP

(71) Applicant: MUUTO A/S, København (DK)

(72) Inventor: Johan Van Hengel, Rotterdam (NL)

(73) Assignee: MUUTO A/S (DK)

() Term: 15 Years

(21) Appl. No.: 35/517,399

(22) Filed: May 16, 2023

(80) Hague Agreement Data

Int. Filing Date: May 16, 2023

Int. Reg. No.: DM/229074

Int. Reg. Date: May 16, 2023

Int. Reg. Pub. Date: Jun. 2, 2023

(30) Foreign Application Priority Data

Mar. 31, 2023 (EM) 015016582-0001

(51) LOC (14) Cl. 26-05

(52) U.S. Cl.

USPC D26/110

(58) Field of Classification Search
